UNITED STATES PATENT OFFICE.

WILLIS A. SUTFIN, OF MARYSVILLE, CALIFORNIA

AUTO CAMP BED.

Application filed February 14, 1925. Serial No. 9,124.

This invention relates to bed structures and particularly pertains to collapsible camp beds.

It is the principal object of the present invention to generally improve devices of the character described by providing them with head and foot boards capable of forming a case to enclose the bed frame when collapsed.

10 It is another object of the invention to provide beds of the character described with an improved spring mattress designed so that a portion of it may be deflected by a load imposed thereon without materially deflecting the entire mattress.

One form which the invention may assume is exemplified in the following description and illustrated by way of example in the accompanying drawings, in which:

20 Fig. 1 is a perspective view of a camp bed embodying the preferred form of my invention.

Fig. 2 is an enlarged fragmentary view of the spring mattress showing its construction.

25 Fig. 3 is a longitudinal section through the end rails of the bed showing the connections between the head and foot boards and the end rails.

30 Fig. 4 is an enlarged view of the connection between the adjacent ends of the sections which constitute each side rail.

Fig. 5 is a sectional view through the end members 22 and 23 in folded position with the bed structure omitted for the sake of simplicity.

35 Referring more particularly to the accompanying drawings, 10 generally indicates a bed frame having a head rail 11, a foot rail 12 and side rails 14. All of these elements 40 are formed of angle iron of dimensions to give them sufficient strength and rigidity.

The side rails 14 are each formed in two sections of different lengths which are pivotally connected at their outer ends to the head 45 and foot rails 11 and 12 so that they may be folded parallel to these latter rails and nested within them. The sections of the side rails connected with the foot rail (likewise those connected with the head rail) are of different lengths, so that both of them may be folded 50 parallel to the foot rail and nested therein to permit the bed to be rolled into a compact bundle for transportation or storage.

55 The inner ends of the sections of the side rails overlap and are detachably connected by a connection shown in Fig. 4. Reference

being had to this figure, it is seen that a hook-like projection 15 projects from the bottom surface of the rail section 14^a and engages a drilled hole 16 in the rail section 14^b. To 60 maintain this engagement and give sufficient rigidity to the connection a cam lever 17 is pivoted to the rail section 14^a, a short distance from the projection 15. The cam end of this lever is adapted to engage the underside 65 of the end of the rail section 14^b and latch it to the rail section 14^a. By swinging the cam lever 17 about its pivotal point, its cam end may be disengaged from the rail section 14^b. This section may then be disengaged from the 70 projection 15 and the rail sections separated.

To support the bed frame, each side rail section is fitted with a pivotal leg 19 which may be folded within and parallel to the side section to which it is pivoted. Each leg 75 is provided with a brace 20 which is pivoted to the leg at one end. The other end is formed with an opening adapted to engage a projection on the adjacent side rail.

A second brace 21 is provided for each leg. 80 This brace is pivoted to the adjacent head or foot rail and is formed with a hooked end for engaging a notched opening 22 in the adjacent leg 19. When the bed is "knocked-down" the brace 21 is folded within the end rail and the brace 20 is folded parallel to the leg. The latter is then folded to nest within the side rail section to which it is attached.

To form head and foot boards I provide 90 semi-cylindrical members 22 and 23 which are arranged transversely of the frame, one adjacent the head rail and one adjacent the foot rail, with their concave surfaces disposed upwardly. The head board 22 is hinged 95 to the head rail so that when the frame is folded compactly it may be folded into the head board 22. The foot board 23 is formed with studs 24 which engage openings in the foot rail to removably support the foot board. 100 When the bed frame is compactly folded into the head board, the foot board is placed thereon and unites with the head board to form a substantially complete cylinder to enclose the bed frame.

105 To latch the head and foot boards together, the latter is formed with latch members 25 which may be engaged with openings 26 formed in the head board.

The spring fabric used in connection with 110 my improved bed frame is more clearly disclosed in Figures 1 and 2. Reference being

had to these figures, it is seen that the fabric comprises longitudinal chains 27 fitted at their ends with tension springs 28 which are connected with the head and foot rails. The 5 chains 27 are spaced apart transversely of the frame and are connected together intermediate the ends of the bed by short transverse links 29. The transverse rows of these links 29 connect alternate pairs of the chains. 10 Likewise, the links of the rows are relatively staggered. By this construction any group of the longitudinal chains may be deflected without deflecting all of the remaining chains. This overcomes the disadvantage of 15 the bed fabrics in which the transverse connections between the chains extended completely across the bed. In this construction, the bed sagged at the point where the greatest strain was put, and the occupant or occupants rolled toward this point because the transverse connections bowed from end to end.

The chains at the sides of my improved fabric are fitted with V-shaped latches 30 25 which may be detachably connected with lugs 31 projecting vertically from the side rails. It will be noticed that these latches 30 occur intermediate the points where the short links 29 connect with the side chains.

30 It is apparent that the fabric here disclosed may be readily rolled up around the frame when the latter is collapsed.

Short braces 21^a are located in diagonally opposed corners of the frame. These 35 braces are pivoted at one end to the end rails and are adapted to be detachably connected at their other ends to the side rails. The braces 21^a fold within the end rails when the frame is collapsed.

40 In collapsing the bed frame and folding it into a compact package for transportation, the foot board is first removed from the end rail and the V-shaped latches on the spring fabric are disengaged from the side rails.

45 The cam levers 17 are then swung about their pivotal points to release the engagement between the overlapping ends of the sections of each side rail. The sections of the side rails are then disconnected from each other by 50 withdrawing the projections 15 on the sections 14^a from the openings 16 in the sections 14^b.

The braces 20 are then disconnected from

the side rails and folded parallel to the legs. Likewise the braces 21 are disengaged from 55 the legs and folded parallel to the end rails. The legs are then swung about their pivotal points and nested within adjacent side rail sections.

After the legs are in position, the side rail 60 sections pivoted to the foot rail are swung parallel thereto and nested within the foot rail. The side rail sections connected with the head rail are likewise folded and nested 65 within the head rail.

The spring mattress or fabric is then rolled up on the foot rail and its nested parts until 70 the foot rail is contiguous to the head rail. The whole is then laid in the head board and the foot board is latched thereto to form a case 75 for the collapsed frame.

The bed may be erected by simply reversing 80 the operation just described.

It should be stated that when the bed is 75 erected, the head and foot boards form ideal 85 holders for fishing rods, guns and like devices.

From the foregoing it is obvious that a simple 90 and efficient bed structure has been provided which may be readily set up for use or collapsed within a case for storage or transportation.

While I have shown the preferred form of 95 my device, it is to be understood that various changes in its construction may be made without departing from the spirit of the invention as defined in the appended claim.

Having thus described my invention, what I claim and desire to secure by Letters Patent is:

A bed frame including end rails, side rails pivoted at their ends to the end rails, legs pivoted to the side rails and foldably thereagainst, said side rails each being formed of two sections of different lengths detachably 95 connected at their adjacent ends whereby their sections may be folded parallel to the end rails and nested therein, a concave head board hinged to one end rail, a concave foot board detachably connected to the other end rail whereby the foot board may be removed and the frame collapsed within the head board, and latch means for connecting the foot board to the head board to form a case 100 for the collapsed frame.

105 WILLIS A. SUTFIN.
